UNITED STATES PATENT OFFICE.

JOHN SUNDGREN, OF DULUTH, MINNESOTA.

PIPE-BENDING DEVICE.

Application filed November 22, 1926. Serial No. 149,809.

This invention relates to pipe bending devices, the principal object of which is to provide a more practical, and simple device of this character than heretofore known.

5 Other objects and advantages of the invention will appear in the further description thereof.

Referring now to the accompanying drawing, forming part of this application, and 10 wherein like reference characters indicate like parts:

Figure 1 is a perspective view of the improved shaping device; and

15 Figure 2 is a perspective view of the end of the jaw adjusting bolts.

1 represents a channel shaped metal frame or body portion to which the bending mechanism is attached, and this form of body portion is particularly designed for engagement with a rectangularly shaped supporting object such as a post, horizontal timber or the like, for securely supporting said body portion. For securing the body portion to the post or other member I have provided the adjustable screw threaded bolts 2 through one side of the channel wall. Upon the back thereof is formed the integral arcuately shaped concavo-convex jaw or bending member 3, though the same may be permanently fixed to the body portion in some other manner if desired. The back of this fixed jaw is provided with a round socket 4 which is internally screw-threaded and in direct alignment with the hole 5 in the laterally projecting lug 6 on the corner of the body portion spaced some little distance from the jaw 3. This arrangement is provided for the insertion of a handle indicated in dotted lines at 7, which may be thrust through the hole 5 and engaged within the socket 4, the end of said handle preferably being screw-threaded for such engagement, so that in the event of not being able to conveniently mount the device upon a post, timber, or the like, a piece of pipe, for example, or rod screw threaded upon its extreme end may be inserted within these aligned holes 4 and 5 and the device thus permanently held in lieu of other means of support.

50 Facing the jaw 3 is a like jaw 8 adjustably supported upon the back of the body portion by means of two externally screw-threaded bolts 9, spaced one above the other and supported within the lugs 10 formed integral with the back of the body. These

bolts are rotatably mounted within the hub-like protrusions 11 on the back of the jaw 8, each bolt having an annular channel 12 spaced a short distance from the extreme 60 end thereof as clearly shown in Figure 2, and the hubs 11 being provided with transverse holes for registration with the channels 12, permitting of a cotter pin 13 being placed therethrough when the bolts are in 65 position within their respective hubs, thus preventing accidental disengagement and yet allowing the bolts to freely rotate without stress upon the jaw. While the opposite ends of the bolts may be provided with 70 heads if desired I have shown them simply as squared, as at 14, for convenient application of a wrench.

The operation of the device is as follows:

The body portion 1 may be clamped upon 75 an upright rectangularly shaped post, if such is convenient, or upon an iron rod such as illustrated at 7 firmly held within a vise for example, when the round iron or pipe as the case may be which is to be bent is inserted vertically intermediate of the jaws 3 and 8, when the bolts 9 may be screwed up until the jaws impinge the material to be bent. The bending is accomplished by applying stress towards the support 7 for example, either or both ends of the material being bent in either direction as desired, only, however, to the curvature represented by that of the jaws, and the adjustability of which may be slackened for feeding the pipe 80 or rod through to any extent desired, when the same may be again tightened for such bending operation. As the bolts 9 are independently adjustable, it is obvious that either end of the adjustable jaw may be set 85 up slightly in advance of the other for the more delicate curvature of the object being bent.

90 From the foregoing it is evident that I have devised an exceedingly simple and practical device wherein a piece of iron or pipe may be conveniently bent and the relative position of the bending jaws adjusted to accommodate different sized pipes, or assist in the bending process.

100 Having thus described my invention, what I claim and desire to secure by Letters Patent, is:

1. A bending device of the class described 110 comprising a channel shaped body portion, means for rigidly holding same, an arcuately shaped concavo-convex jaw fixed to one face

thereof, a second jaw spaced from the first mentioned jaw and of similar shape, and spaced adjusting means for independently moving opposite ends of the last mentioned

5 jaw.

2. A bending device of the class described comprising a body portion, a fixed arcuately shaped jaw upon one face thereof and an

opposite similarly shaped jaw normally spaced therefrom, and a pair of spaced adjustable supporting bolts for said latter jaw for the purpose described.

In testimony whereof I affix my signature.

JOHN SUNDGREN.
